UNITED STATES PATENT OFFICE.

ARTHUR K. MITCHELL, OF BRONXVILLE, NEW YORK, ASSIGNOR TO ST. JOSEPH LEAD COMPANY, OF NEW YORK, N. Y., A CORPORATION OF NEW YORK.

UNDERGROUND MINING MACHINE.

Application filed October 2, 1922. Serial No. 591,689.

To all whom it may concern:

Be it known that I, ARTHUR K. MITCHELL, a citizen of the United States, and a resident of Bronxville, county of Westchester 5 and State of New York, have invented certain new and useful Improvements in Underground Mining Machines, of which the following is a specification.

This invention relates to an improved 10 underground mining machine and is in part, a continuation of my prior application for patent filed July 21st, 1920, Serial No. 397,881.

Generically considered, it is the primary 15 object and purpose of this invention to provide a machine of the above character which is especially designed for operation in mine corridors of limited height, and which will be exceedingly mobile and can be readily 20 operated in a comparatively restricted space, as for instance, between the roof supporting pillars, in the loading of the transporting vehicles with ore.

It is another object of my invention to 25 provide an improved system of control enabling the operator without changing his position upon the machine, to properly manipulate the ore collecting dipper or shovel and to position the same above the ore 30 receiving and transporting vehicle, or to effect the bodily movement or travel of the machine.

The present invention also contemplates 35 the provision of an improved mounting for the dipper or shovel carrying boom and means for imparting a longitudinal forward thrust or retracting movement to the boom so that the shovel or dipper after being filled, may swing with the superstructure of 40 the machine between spaced roof supporting pillars in the mine corridor and thus dispose the shovel in a dumping position over the ore receiving vehicle.

In one practical embodiment of the invention I provide a rotatable superstructure 45 mounted upon a tractor supported frame and a longitudinally traveling shovel-carrying boom carried by the superstructure. Three electric motors of the reversible type 50 are mounted upon the superstructure and each connected in suitable electric circuits, one of said motors operating the tractor actuating mechanism or the boom actuating mechanism, another of said motors actuating 55 the boom hoisting means, while the third

motor actuates the superstructure rotating means. By the manipulation of suitable circuit controlling switch levers, the operator may render one, or simultaneously two or three, of the motors operative to effect the desired operation, each of the motors being preferably equipped with a magnetic brake so that when its circuit is broken, the operation of the motor is instantly stopped.

It is also one of the detailed objects of the invention to provide ample automatic means for breaking the circuit of the boom operating motor to limit the forward thrusting movement and the retracting movement of the boom, and also to provide automatic 65 circuit-breaking means for the hoist motor to limit the elevated position of the shovel or dipper as well as to stop the hoist motor, when during its lowering motion the shovel or dipper strikes the mine floor or other 70 obstruction.

Another of the detail objects of the invention is to provide simple and efficient means acting to positively lock the tractors against movement to hold the machine as a whole, in 80 a stationary position while the boom and shovel are being operated to gather and load the ore.

In accomplishing the aforementioned objects I have at the same time succeeded in 85 devising a machine primarily designed for underground mining operations which, in view of its manifold capabilities, is of relatively simple construction, light in weight, and wherein the various operating parts are 90 compactly arranged and not liable to get out of order.

With the above and other objects in view, the invention consists in the improved form, construction and relative arrangement of the 95 several elements, as will be hereinafter more fully described, illustrated in the accompanying drawings and subsequently incorporated in the subjoined claims.

In the drawings wherein I have illustrated one practical embodiment of the invention and in which similar reference characters designate corresponding parts throughout the several views,

Figure 1 is a top plan view of an underground mining machine, constructed in accordance with my present invention;

Figure 2 is a side elevation of the machine, the boom and shovel being shown in full lines in its lowered retracted position.

and in dash lines in the retracted elevated position, the shovel being illustrated in dotted lines in dumping position;

Figure 3 is a front elevation of the machine;

Figure 4 is a longitudinal section taken on the line 4—4 of Figure 1;

Figure 5 is a detail side elevation of the tractor supported frame, the superstructure being removed;

Figure 6 is a transverse section taken on the line 6—6 of Figure 1;

Figure 7 is a front end elevation of the tractor frame, the tractors being shown in section;

Figure 8 is a top plan view partly in section of the superstructure supporting frame;

Figure 9 is an enlarged plan view with certain parts shown in section to more clearly illustrate the driving connection between the motors and the superstructure rotating mechanism and the tractor actuating mechanism;

Figure 10 is a sectional view through one of the motor brakes with parts thereof in elevation, taken on the line 10—10 of Figure 1;

Figure 11 is a section taken on the line 11—11 of Figure 10;

Figure 12 is an end elevation of the brake;

Figure 13 is a detail sectional view through the brake engaging wheel on the shaft of the boom operating motor and illustrating the manually operable clutch connection between said wheel and the boom operating gearing;

Figure 14 is an enlarged detail section showing the universal connection between the boom gudgeons and the carriage blocks mounted for longitudinal movement on the superstructure of the machine, said section being taken on the line 14—14 of Figure 1;

Figure 15 is a transverse section taken on the line 15—15 of Figure 1, showing the worm gear driving connections between the operating motors and the hoisting drum and boom operating shaft respectively;

Figure 16 is a diagrammatic view showing the boom and shovel in full lines in the fully extended lowered position with relation to the machine superstructure and in broken lines in various other positions which the boom and shovel may assume in the operations of hoisting and dumping the material;

Figure 17 is a diagrammatic view showing a conventional wiring of the electric motor controlling circuits with the operator's control levers and the automatic circuit breaking devices;

Figure 18 is an enlarged detail plan view, partially diagrammatic illustrating the relation of its several control levers with respect to the operator's seat;

Figure 19 is an enlarged plan view show-

ing the actuating means for the forward and rear limit switches of the boom operating motor;

Figure 20 is a detail elevation of the actuating means for the forward limit switch;

Figure 21 is a section taken on the line 21—21 of Figure 19;

Figure 22 is a detail elevation of the lower limit switch for the hoisting motor;

Figure 23 is a section taken on the line 23—23 of Figure 19;

Figure 24 is a detail elevation of the operating means for the rear limit switch of the boom operating motor;

Figure 25 is a longitudinal section on the centre line of the dipper or shovel, which section intersects the shovel and boom head, together with the latch device;

Figure 26 is a side view of the dipper or shovel and a longitudinal section through one of the spring bumpers or shock absorbers; and

Figure 27 shows details of the frame or bracket carrying the collector shoes.

In the embodiment of the invention illustrated in the accompanying drawings as shown by Figs. 2, 3, 4, 5, 6, 7, and 8, the supporting frame 5 for the tractor of the machine is of general rectangular form in plan and includes a centrally elevated body portion 6 at each end of which and at the opposite sides of the frame, the longitudinally extending bearing supports 7 and 8, respectively, are formed. The frame extensions 7 receive the bearings 9 for one end of the respective tractor driving shafts 10 which are located at opposite ends of the frame 5. The inner ends of the shafts 10 are journaled in suitable bearings provided in the lower portion of a housing 11, said housings being respectively secured centrally to each end of the body 6 of the frame.

Upon the frame extensions 8 longitudinally adjustable bearings 12 are mounted in which shafts 13 are journaled. Any conventional means may be employed for the purpose of adjusting the bearings 12 relative to the frame structure.

At each side of the machine, the endless tractor treads 14 are engaged upon the sprocket wheels 16 and 17 secured respectively upon the outer ends of the shafts 10 and 13 which project from each side of the machine frame. The flexible tractor treads between the spaced sprockets are supported and guided by means of a plurality of flanged rollers 18 suitably mounted upon spaced stud shafts fixed in each side of the machine frame. The tractor driving shafts 10 are actuated to propel the endless flexible treads in either direction by means of mechanism which will be presently described.

Upon the body portion 6 of the frame 5 an annular toothed rack 19 is securely fixed to

the frame 5 and the teeth of the rack 19 are meshed with the teeth of the sprocket wheels 16 and 17.

in any preferred manner and within this annular rack a plurality of concentrically spaced electric current collector rings 20 are supported in parallel spaced relation to the frame body by means of suitable insulators 21.

The superstructure of the machine upon which the primary parts of the operating mechanism are mounted and arranged consists of a substantially rectangular platform 22, as shown by Figs. 1, 2, 4, and 6, said platform having a tubular bearing standard 23 centrally fixed therein, the lower end of said standard being engaged within an upwardly projecting boss 24 formed upon the frame body 6. The platform 22 is provided at its opposite sides with depending longitudinally extending walls 25, said platform being also formed with an annular depending flange 26 surrounding the rack 19, said flange merging into the walls 25 at opposite sides of the superstructure. To the lower edge of the flange 26 a ring or annulus 27 is fixed and projects inwardly beneath the lower edge of the rack 19 and thus prevents an oscillating movement of the rotatable superstructure with respect to its axis. The means whereby this superstructure, together with the operating mechanism mounted thereon, may be rotated with respect to the tractor supported frame 5, will also be fully disclosed in the subsequent description.

As shown by Figures 6 and 14, to the outer face of each of the depending walls 25 of the superstructure platform 22, a channel bar 28 is secured by means of the bolts 29, said bolts passing transversely through guide rails 30 which are secured upon the channel bar flanges in opposed relation to each other. The longitudinally extending ribs 31 of the guide rails 30 are engaged in suitable channels provided in the carriage blocks 32 whereby said blocks may freely travel longitudinally between the guide rails. To opposite sides of each carriage block 32 the ends of a link type sprocket chain 33 are pivotally connected, a turn buckle 34 or other suitable slack take-up means being interposed in the length of this chain, as illustrated in Figure 2. The chains 33 engage with the sprockets 36 mounted upon shafts suitably supported on the forward end of the superstructure, said chains being positively driven by the sprockets 37 which are fixed upon opposite ends of a transverse shaft 38 journaled in suitable bearings on the rear end of the platform 22.

The shovel or dipper carrying boom as herein illustrated, consists of tubular side members 39 which are connected at their forward ends by means of a boom head 40; Figures 1, 2, 3. The members 39 at their rear ends are supported from the carriage blocks 32 in the manner clearly shown in

Figure 14 of the drawings, wherein it will be noted that a gudgeon 41 extends transversely through each boom member and projects from one side thereof, said gudgeon being suitably fixed to the boom member 70 as by means of the pin 42. The projecting end portion of the gudgeon 41 is reduced in diameter and tapered as at 43, said tapered end of the gudgeon being tightly drawn into the bore of a universally movable socket member 44 shaped as a zone of a sphere, mounted in the carriage block 32 by means of the nut 45 which is engaged upon the reduced threaded projection 46 of the tapered end 43 of the gudgeon. There are thus provided substantial connections between the boom members and the traveling carriage blocks which allow a free vertical pivoting or rocking movement of said boom members relative to the carriage blocks when the boom, together with the shovel or dipper carried thereby, is hoisted or lowered with respect to the superstructure of the machine. Since these connections are of the ball and socket type, the carriage blocks 32 cannot be subjected to any eccentric or torsional stresses due to any side thrust on boom or dipper.

From the above it will be seen that the means for projecting and retracting the boom consists of the sprocket chains 33 driven by the sprockets 37 and the carriage blocks 32 upon which the side arms or members 39 of the boom are mounted at their rear ends. This boom operating means is actuated by a reversible motor to be hereinafter referred to, and in certain of the subjoined claims I have included this motor or primary power source as an element separate from the boom operating means as above defined.

The dipper, bucket, shovel or skip, as it is variously termed, may be of any suitable or preferred construction, in so far as the essential features of the present invention is concerned and it may be mounted upon the boom head in various ways. However, for purposes of illustration I have herein shown the shovel 47 as an open top scoop, Figures 1, 2, 3, 16, 25, and 26, pivotally mounted for a tilting movement upon the trunnions or pins 48 fixed in the downwardly and forwardly projecting arms 49 of the boom head 40. Figure 25 is a central longitudinal section through shovel 47 and boom head 40. The shovel is so constructed and counterbalanced that when loaded with ore or other material the center of gravity of the shovel and its load lies forward of pins 48, thus causing forward tilting and dumping when the loaded shovel is unlatched and free to move. The centre of gravity of the shovel when empty lies behind the pins 48; therefore, when free to tilt the empty shovel will return by gravity to its normal or digging

position. Shovel 47 is held in this latter position by latch 401 which engages the upper end of lug 402. Latch 401 is held against rear end of shovel 47 by compression of spiral spring 403 which is mounted on rod 404 in an annular recess in boom head 40. To empty the loaded and elevated shovel, the operator presses down a pedal located conveniently near his feet, which motion overhauls a spring-actuated retrieving drum upon which cable 405 is wrapped, causing cable 405 to pull lever 406 thus disengaging latch 401, to which lever 406 is attached, from upper end of lug 402, thereby permitting shovel 47 to tilt forwardly and discharge its load. When the forward tilting movement is arrested, as hereafter described, latch 410 engages the lower end of lug 402, thus holding shovel 47 in position of maximum inclination so that its load of ore may be completely discharged. Latch 410 is held against rear end of shovel 47 by pressure of spring 403 through rod 404. Another pull on cable 405 causes lever 406, through its connections with latch 401 and rod 404 to disengage latch 410 from lower end of lug 402, thus permitting the empty shovel to tilt backwardly to its normal or digging position, such backward tilting being limited by the striking of buffers 411, of which there is one on each side of the shovel, against arms 49.

Figure 26 is a side view of shovel 47 in its tilted position, showing also a section 35 through one of the two spring bumpers or shock absorbers 407, but omitting details of the latch mechanism. The positions of spring bumpers 407 are also shown by Figures 1, 2 and 3. When shovel 47 is allowed to tilt forward to dump its load, its movement is arrested by the engagement with lugs 409, of which there is one on each side of the rear end of shovel 47, of hooked ends of plungers 408, said plungers acting under the impact to compress springs 412, thus absorbing the shock. Springs 412 are mounted within cylindrical members 407 which are attached to boom head 40.

A sheave block 50 is suitably connected 50 centrally to the boom head 40 and around the sheave therein the cable 51 is engaged; Figures 1, 2 and 3. This cable is trained over and supported by the spaced pulleys or sheaves 52 which are rotatably mounted 55 upon a common axis 53 extending between the upper ends of the standards 54, said standards at their lower ends being pivotally mounted as at 55 upon the superstructure platform 22. The forward ends of longitudinally extensible rods 56 are also loosely engaged upon the pulley axis 53 at the outer side of each pulley 52, said rods diverging with respect to each other in a rearward direction and being pivotally mounted at their rear ends as at 57. These rods 56 may each be

of the conventional sectional telescopic construction, suitable means, of course, being provided to securely hold the rod sections in fixed relation to each other. Thus, when it is necessary to propel the machine through a connecting passageway or corridor of very limited height, the standards 54 may be readily swung forwardly and downwardly to a lowered position as indicated by broken lines in Figure 2 of the drawings. 75

One strand of the cable 51 extends rearwardly and downwardly from one of the pulleys 52, and is suitably connected to the hoisting drum 58 which is fixed upon or integrally formed with a sleeve 59 loosely mounted upon the shaft 38 for independent rotation; Figures 9 and 15. The other strand of the cable 51 extends over a pulley or sheave 60 mounted in the upwardly extending arm of a bracket 61 which is provided for pivotal or rocking motion upon a shaft 62 for a purpose which will be hereinafter explained. From this sheave 60 the cable strand extends rearwardly and is suitably attached at its end to the larger end 90 of a fusee drum 63 which is keyed or otherwise rigidly fixed upon the shaft 38. The fusee drum 63 is so designed that the cable 51 will be unreeled from it at a variable rate such that when the dipper is being 95 crowded out by the operation of motor 69 as hereinafter described, starting with the dipper lip on the plane of the tractor bottom, the path described by the dipper will be horizontal. By reference to Figures 2 100 and 16 it will be understood that the boom is projected, or crowded out an equal distance for each degree of revolution of shaft 38. As the boom and sheave 50 move out, if the lip of the dipper is to travel a horizontal path on the plane of the tractor bottom, cable 51 must be unreeled at a progressively increasing rate, which rate, since the cable is a two part one, must equal at 105 any point twice the corresponding increment in the distance between the points of contact of the cable with sheaves 52 and sheave 51. A plain cylindrical drum, keyed to shaft 38, would unreel an equal 110 length of cable for each degree of revolution of shaft 38 causing an outward and upward path of the dipper; therefore, a fusee drum designed as explained, is provided. 115

The sleeve 59 of the hoisting drum 58 has 120 a worm gear 64 fixed thereon with the upper side of which a worm 65 on the shaft 67 of the hoisting motor 66 is engaged; Figures 1, 9 and 15. This worm and worm gear are enclosed within a suitable housing 125 68 mounted on the platform 22. It will thus be apparent that by the operation of the motor 66, the hoisting mechanism can be actuated to lift the boom and hoist the loaded shovel carried thereby to the desired 130

height, while the shovel is in its forwardly projected position, in its retracted position, or in any intermediate position.

There is also mounted upon the super-
5 structure platform 22, a second electric motor 69 which operates the boom thrusting and retracting mechanism and also the tractor propelling mechanism of the machine; Figures 1, 2, 4, 7 and 9. A third
10 electric motor 70 mounted on the platform 22 actuates suitable gearing cooperating with the fixed rack 19 to rotate the super-structure upon the main frame 5. Each of these motors is of the reversible type and
15 is equipped with a conventional form of magnetic brake. These brakes I have indicated in the accompanying drawings by the numerals 71, 72 and 73 respectively. I have also illustrated one of the magnetic
20 brakes in detail in Figures 10, 11 and 12 of the drawings. It will suffice for the purpose of the present explanation to state that each brake includes opposed magnetically controlled brake shoes 74 which are adapt-
25 ed for frictional braking engagement upon opposite sides of a wheel 75 fixed in any suitable manner upon the motor shaft. The brake shoes 74 normally engage wheel 75 under the spring action; when, however,
30 the magnet or solenoid coil is energized, the shoes are magnetically pulled away from the wheel, against said spring action, thus releasing the brake for free operation of the motor.

35 Upon the end of the shaft of the motor 69 a clutch element 76 is loosely engaged, Figure 13, said element being fixed within one end of a sleeve 77 which extends over one end of the hub portion 78 of the wheel
40 75. A friction band is carried by the block 79 fixed to the wheel hub and is interposed between the hub wall and the wall of the sleeve 77. A spring pressed wedge member 80 extends between spaced ends of the
45 friction band and acts to hold the same in tight frictional engagement with the wall of the sleeve 77. It will thus be apparent that there is obtained in this manner a slip friction connection between the clutch ele-
50 ment 76 and the wheel 75 which is fixed on the motor shaft. This device is designed to slip in the event of severe overloads or sudden impacts, such as would be caused during forward crowding by the shovel
55 striking an immovable obstruction. Motor 66, which operates the hoisting drum 58 is provided with a similar device, as is motor 70, which operates the swinging mechanism, hereinafter described.

60 A manually shiftable complementary clutch element 81 is keyed upon the shaft 82 which is journaled in the upper part of a housing 83 enclosing the worm gear 84 fixed on the shaft 38 and the worm 85 on said
65 shaft 82 which is engaged with the worm

gear 84; Figures 1, 2, 9 and 13. It will thus be apparent that when the clutch ele-
70 ment 81 is engaged with the complementary clutch element 76, rotation is transmitted from the motor through shaft 82 and worm 75 gearing 84 and 85 to the shaft 38 which drives the boom carrying chains 33 to move the boom in the desired direction and either thrust the shovel 47 forwardly to gather the ore therein or to retract the shovel, from
75 which position it may be subsequently hoisted and disposed over the receiving and transporting vehicle. The other end of the shaft of the motor 69 is also provided with a clutch member 86 with which a comple-
80 mentary clutch member 87 keyed upon the shaft 88 is adapted to co-act; Figures 1, 2 and 9. Between motor 69 and said clutch elements there is also provided a slip friction device, similar to that previously de-
85 scribed but not shown by the drawings. Shaft 88 is journaled in the upper end of a housing 89 and is provided with a worm 90 which is engaged with the worm gear 91 on a transversely positioned shaft 92 mounted 90 in the housing walls, Figure 6. Upon the inner end of this shaft a beveled gear 93 is fixed and meshes with a similar gear 94 keyed upon a tubular shaft 95 mounted in the hollow standard 23 fixed in the super-
95 structure platform 22. The inner end of shaft 92 is also journaled in one side of this standard. The lower end of the shaft 95 extends below standard 23 and has a beveled gear 96 fixed thereon which is in mesh at 100 diametrically opposite points with the gears 97 and 98, respectively, Figure 4. The gear 97 is keyed or otherwise fixed upon the end of a rearwardly extending shaft 99. The end of this shaft is suitably coupled at the rear side of the frame body 6 to a shaft 100 journaled in the upper side of the housing 11 in which the inner end of the rear tractor operating shaft 10 is mounted. The shaft 100 is provided with a worm 101 meshing 105 with the worm gear 102 on the shaft 10.

The other gear 98 is loosely mounted upon a forwardly extending shaft 103 which, at the front side of the frame body 6, is suitably coupled to a shaft 104 journaled in the upper side of the housing 11 supporting the other tractor operating shaft 10. This shaft 104 is likewise provided with a worm 105 meshing with the worm gear 106 on said 115 tractor operating shaft.

The shafts 99 and 103 are supported in suitable bearings adjacent to the gears 97 and 98 respectively, which are mounted in webs or hangers 107 depending from the frame body 6. A spider 108 is arranged within the lower end of the boss 24 on the frame body 6 and the upper ends of the arms of a yoke 109 are pivotally mounted in this spider, Figures 4 and 6. The yoke arms are provided with rollers 110 engaged 120
125
130

in opposite sides of a peripheral groove formed in a double acting clutch collar 111, said collar having clutch teeth on each of its side faces to engage with similar clutch 5 teeth on the gears 97 and 98 respectively, and being mounted for longitudinal sliding but not for rotation upon end of shaft 103. A bar 112 is swiveled at its ends in the lower ends of the arms of the yoke 109 and 10 to this bar oppositely projecting axially movable rods 113, are suitably connected, said rods sliding through suitable bearing guides 114 in the hanger webs 107. Each 15 of said rods 113 at its other end is connected to a slide block 115 supported by the roller 116 mounted in a bracket plate 117 suitably fixed to the frame 5. A bell crank lever 118 is also fulcrumed in each of the bracket plates 117, one arm of the lever projecting 20 upwardly and being operatively connected with a sliding locking clutch member 119 keyed upon the shaft 99 or 103. These locking clutches are adapted to normally engage with a fixed part 120 surrounding the shaft 25 and depending from the frame body 6 whereby said shafts 99 and 103 are locked against rotation. The bell crank levers are urged to this normal position by means of coil springs 121 engaging the other or horizontal arms of said levers and interposed between said arms and the fixed parts 120, said springs also acting to yieldingly hold rollers 122 carried by the lever arms in the recesses or seats 123 provided in the upper 30 surfaces of the slide blocks 115.

Within the tubular shaft 95 a rod or shaft 124 is loosely mounted and is provided at its upper end with a hand wheel 125 whereby said rod may be conveniently rotated, 40 Figure 6. The lower end of this rod carries a pin or stud 126 eccentrically offset from the axis of the rod and engaged in a slot 128 provided in a connecting bridge 127 between the arms of the yoke 109. It will thus be 45 apparent that when this rod 124 is rotated, the pin 126 coacting with the walls of the slot 128 acts to shift the yoke 109 in one direction or the other, and thereby engage the clutch collar 111 with the gear 97 or 50 the gear 98, as the case may be, and to also simultaneously shift the rods 113 so as to actuate the bell crank levers 118 and thereby release the locking clutches 119 from engagement with the parts 120. When the collar 55 111 is shifted to the left from the position seen in Figure 6, it will be obvious that the shaft 103 is connected through the medium of said collar and the gear 97 to the shaft 99 so that both shafts will rotate as a unit. 60 Thus both of the flexible tractor treads will be driven in the same direction for a straight line movement of the machine. When the collar 111 is shifted in the opposite direction and engaged with the gear 98, said

gear is locked to the shaft 103 so that rotation will be imparted to this shaft from the gear 96 in a direction opposite to the direction of rotation of the other shaft 99. The tractor treads will thereby be moved in relatively opposite directions so that the machine 65 can be turned or manoeuvred in a comparatively restricted space.

The clutches 81 and 87 are manually actuated to operatively connect the motor 69 to the boom operating gearing or to the 70 tractor operating gearing as the case may be, through the medium of a lever 224 which is pivotally mounted upon one side of the gear housing 89, Figure 9. This lever is provided with an upper arm 225 connected 75 by the rod 226 to a swinging yoke 227 in which the shiftable clutch member 87 is carried. The lever 224 is also provided with a second arm 228 connected by the link 229 to one end of a lever 230 which is fulcrumed 80 intermediate of its ends upon the superstructure platform 22, the other end of said lever being connected by a rod 231 to the lower part of yoke 232, (Figure 2) which is so fulcrumed on platform 22 that its lower part 85 engages the shiftable clutch element 81. As seen in Figure 9, when the lever is moved in one direction toward the center line of the machine, the clutch element 81 is thrown out to disconnect the motor from the gearing 90 operating the boom while the other clutch element 87 is thrown into engagement with the clutch 86 to connect said motor to the 95 gearing operating the tractors. Upon shifting this lever away from the center line of the machine, such condition is reversed and the motor is connected in driving relation with the boom operating gearing and disconnected from the tractor operating 100 gearing.

The superstructure platform with the motors and mechanisms mounted thereon is rotated with relation to the supporting frame 5, as indicated by the broken line shown in Figure 1, by means of the gearing illustrated in Figures 4 and 9 of the drawings, from reference to which it will be noted that the shaft extension 134 from the motor 70 is provided with a worm 135 meshing with the worm gear 136 on the upper end of a perpendicular shaft 137 mounted in suitable bearings on the platform 22. A pinion 138 is fixed to the lower end of this shaft and meshes with the gear 139 on the upper end of a second perpendicular shaft 140. The lower end of this shaft 140 is in turn provided with a pinion 141 which directly engages with the teeth of the fixed annular rack 19 secured upon the frame body 6. The upper face of this rack is obliquely inclined as at 142 and upon the same suitably spaced frusto-conical rollers 143 mounted in the platform 22 are engaged,

whereby the superstructure and the parts carried thereby will be adequately supported.

Each of the three collector rings 20 is connected with one phase of the three phase alternating current circuit to which, by means of an insulated three-wire cable, the tractor or truck, is wired. Each of these rings is normally engaged by a collector shoe 144 *a*, *b*, or *c*; Figures 17 and 27. The three collector shoes are mounted on a single fibre board 503, the spindles 512 of the shoes sliding loosely through holes in board 503, and shoes 144 are pressed downwards by springs 502 through which pass spindles 512. Each collector shoe 144 is kept in alignment with its collector ring 20 by a toggle connection with fibre board 503. Fibre board 503 is rigidly mounted upon three bolts 508 which pass upwardly with a sliding fit through holes in bracket 501 to a rigid connection with plate 511, bracket 501 being bolted over a suitably located aperture in platform 22. Plate 511, bolts 508, fibre board 503 and collector shoes 144 *a*, *b*, and *c*, are normally held down in position in which rings 20 are engaged by shoes 144 by latch 504 which is pivoted to bracket 501 by pin 509, a notch in latch 504 being pressed against the edge of a hole in plate 511 by leaf spring 505. Latch 504 is connected by rod 160 with lever 152 which is conveniently located near the left hand of the operator, being pivotally connected at 510 with platform 22. If the operator desires to disengage shoes 144 from rings 20, he presses the upwardly projecting forward end of lever 152 to his left, thus disengaging latch 504 from plate 511, permitting plate 507, bolts 508, fibre board 503, and shoes 144 to rise under the action of spring 506, until shoes 144 are lifted clear of rings 20 and all current is thereby cut off from the circuits on platform 22. To re-engage shoes 144 with rings 20, the operator presses downward on guard 507 attached to plate 511, until notch in latch 504 snaps over edge of plate 511.

In Figure 17 I have diagrammatically represented the various motors, brakes, switches, circuit breakers, contactors, and controllers, together with the circuits connecting them. There are three three-phase alternating current squirrel cage reversible motors, of a type having high resistance, high starting torque and low starting current. Each motor has two primary circuits, one for each direction of each motor, and each of these circuits may be completed by means of double pole magnet switches or contactors which are closed when their magnets are energized by the manual closing of pilot or secondary circuits at the two master controllers, the central elements, or levers, of which are indicated at 151 and 153.

If the operator desires to cause the boom and dipper to crowd out, he pushes lever 151 against contact A, Figures 17 and 18. The following secondary circuit is thus completed:—from collector shoe 144^b, through points 301, 302, 303, and 304 to safety fuse 305, to closure between central lever 151 of master controller and contact A, to limit switch 157 (here assumed closed), through magnet coil 147^c to point 306, through contacts of circuit breakers 307 and 308 to point 309, through point 310 to collector shoe 144^c. Since magnet coil 147^c is energized by this secondary circuit, the main contacts 147^a and 147^b are closed, thus completing the main circuit of motor 69 to cause forward motion of boom and dipper. This main circuit is as follows: from collector shoe 144^a through points 311, 312 and 313, through closure of contacts 147^a to point 314, through solenoid coil of circuit breaker 307 to terminal 315 of motor 69; from terminal 316 to point 317, through solenoid coil of circuit breaker 308 to point 319, through closure of contacts 147^b to point 320, through points 321 and 310 to collector shoe 144^c. Regardless of any switch positions, terminal 322 of motor 69 is always connected through points 323 and 301 with collector shoe 144^b. A circuit is simultaneously closed from point 317 to terminal 324 of brake 72 of motor 69, from terminal 325 through point 326 to point 323, said points 317 and 323 being on main circuit of motor 69 previously outlined. Also, when magnet coil 147^c is energized, auxiliary contacts 147^d are closed, thus completing the following secondary circuit: from collector shoe 144^b through points 301, 302, 303 to 304, through closure of auxiliary contacts 147^d through point 327 to point 328, through magnet coil 154^c, through points 329, 330 and 311 to collector shoe 144^a. Since magnet coil 154^c is energized, the main contacts 154^a and 154^b are closed, thus completing the following circuit: from collector shoe 144^b through points 301 and 302 to point 330, through closure of contacts 154^b to terminal 332 of brake 73 of motor 70, from terminal 333 through closure of contacts 154^a to point 331, through point 311 to collector shoe 144^a. From the above it is apparent that the manual closure of lever 151 and contact A causes crowd motor 69 to operate in such a direction as to cause an outward motion of boom and dipper, and simultaneously energizes and therefore releases magnet brake 72 of motor 69, thus permitting motor 69 to function, as well as also releasing magnet brake 73 of swing motor 70, thus permitting platform 22 to rotate slightly and relieve structural stresses should the bucket receive a glancing thrust during

its forward digging motion. Motor 69 will continue to operate and magnet brakes 72 and 73 will remain released unless or until the secondary circuit passing through magnet coil 147^c is opened by (a) the operator breaking the closure between lever 151 and contact A, (b) the opening of limit switch 157 by the motion of the boom as herein-after described, (c) the opening of either 10 circuit breaker 307 or circuit breaker 308, or (d) the burning out of safety fuse 305. Upon such opening of the secondary circuit magnet coil 147^c becomes de-energized and the movable element of the contactor opens 15 by gravity, thus breaking the primary circuit at contacts 147^a and 147^b and also the auxiliary circuit at contacts 147^a. The breaking of this auxiliary circuit de-energizes magnet coil 154^c causing contacts 154^a 20 and 154^b to open by gravity, thus breaking the circuit through magnet brake 73. The circuit breakers such as 307 or 308 are of the usual type, consisting of a solenoid coil in the primary motor circuit which coil 25 rounds a core attached to contact points in the secondary circuit. The movement of the core is normally prevented by an oil dash pot, but if there be a surge of current in the main circuit such as would be caused by a sudden overload, the pull of the solenoid 30 upon its core becomes sufficient to overcome the resistance of the dash pot, thus causing the core to slightly move and open the contacts in the secondary circuit.

35 To cause a rearward or retracting motion of the boom and dipper, the operator pushes lever 151 against contact B, thus closing the following secondary circuit: from collector shoe 144^b through points 301, 302, 303 and 304 to safety fuse 305, to closure between lever 151 and contact B, to limit switch 158 (here assumed closed), through magnet coil 148^c to point 306, through contacts of circuit breakers 307 and 308 to point 309, through point 310 to collector shoe 144^c. The consequent energizing of magnet coil 148^c closes contacts 148^a and 148^b, thus completing the following primary motor circuit: from collector shoe 144^a through points 311, 312 and 313, through closure of contacts 148^a, through solenoid coil of circuit breaker 308 to point 317, to terminal 316 of motor 69, from terminal 315 through solenoid coil of circuit breaker 307, through closure of contacts 148^b 45 to point 321, through point 310 to collector shoe 144^c. The circuit through magnet brake 72 of motor 69 is simultaneously closed as before from point 317 to terminal 324, from terminal 325 through point 326 to point 323. Thus motor 69 is caused to operate and its brake 72 is energized and released. Since two of the three phases of the alternating current supply are connected to the terminals of motor 69 in a sequence 50 transposed from the previous one, the rotor of said motor revolves in an opposite direction, causing an opposite motion of the boom and dipper.

To hoist or elevate the boom and dipper the operator pushes lever 151 against contact D, closing the following secondary circuit: from collector shoe 144^b, through points 301, 302, 303 and 304, through safety fuse 305 and closure between lever 151 and contact D, through limit switch 156 (here assumed closed), through magnet coil 146^c to point 318, through switch 334 (here assumed closed), through contacts of circuit breakers 336 and 337 to point 309, through point 310 to collector shoe 144^c. The energizing of magnet coil 146^c closes contacts 146^a and 146^b, thus completing the following primary circuit: from collector shoe 144^a through points 311, 312 and 338, through closure of contacts 146^a to point 339, through solenoid coil of circuit breaker 336 to terminal 340 of motor 66, from terminal 341 to point 342, through solenoid coil of circuit breaker 337 to point 343, through closure of contacts 146^b to point 344, through points 321 and 310 to collector shoe 144^c. Regardless of any switch positions terminal 345 of motor 66 is always connected through points 346, 326, and 301 with collector shoe 144^b. A circuit is simultaneously closed from point 342 to terminal 347 of magnet brake 71 of motor 66 and from terminal 346 through points 326 and 301 to collector shoe 144^b. Also, when magnet coil 146^c is energized auxiliary contacts 146^d are closed, thus completing the same secondary circuit previously described in connection with auxiliary contacts 147^d, which circuit energizes magnet coil 154^c closing contacts 154^a and 154^b, the latter of which complete the circuit which energizes and therefore releases magnet brake 73 of motor 70, thus permitting platform 22 to turn freely and relieve any transverse stresses should the bucket receive a glancing sidewise thrust while being hoisted.

To lower the boom and dipper it is necessary to cause motor 66 to operate in a reverse direction from that necessary during hoisting. To effect this, the operator pushes lever 151 against contact C, thus completing a secondary circuit from collector shoe 144^b, through points 301, 302, 303 and 304, through safety fuse 305, through closure of lever 151 and contact C, through limit switch 155 (here assumed closed), through magnet coil 145^c to point 312, through switch 334 (here assumed closed), through the contacts of circuit breakers 336 and 337, through points 309 and 310 to collector shoe 144^c. The energizing of magnet coil 145^c causes contacts 145^a and 145^b to close, thus completing the following primary circuit: from collector shoe 144^a through points 311, 312 and 348, through closure of contacts 145^a, through solenoid coil of circuit breaker 337, through point 11

12

342 to terminal 341 of motor 66, from terminal 340 through solenoid coil of circuit breaker 336, through closure of contacts 145^b to point 349, through points 321 and 310 to 5 collector shoe 144^c. The connections of terminals 340 and 341 of motor 66 are thus transposed from those made by the hoisting circuit, and motor 66 is thus caused to operate in the reverse direction. Magnet brake 10 71 is released as before by being energized by the circuit from point 342 to terminal 347, from terminal 346 through points 326 and 301 to collector shoe 144^b.

Motors 66 and 69 may be operated simultaneously, each in either direction. If lever 151 is pressed against contacts A and D it is apparent that there will result both crowding out and hoisting of the boom and dipper. Similarly, if said lever is pressed 20 against contacts D and B, there will be hoisting and retracting, if against contacts B and C, there will be retracting and lowering, and if against contacts C and A, there will be lowering and crowding out.

25 In addition to actuating certain clutch elements previously described, the lever 224 operates a pair of switches, 334 and 335, the movable elements of which are respectively those nearest the forward and rearward ends 30 of the machine. When lever 224 is moved to the travel position in which motor 69 is connected with the gearing operating the tractor, said position being shown at 224^a, it is apparent from Figure 17 that switch 334 35 will be opened and switch 335 will be closed. Since switch 334 is in the secondary circuits which energize magnet coils 146^c and 145^c it therefore becomes impossible for a careless motion of the operator's right hand to activate hoist motor 66 while the machine is traveling, this safeguard being particularly valuable when the machine is being moved through low passageways to clear which it becomes necessary to lower A-frame 54, thus 40 making slack cable 51. Since switch 335 is in the secondary circuit which energizes magnet coil 148^c and is connected in parallel with limit switch 158, it becomes possible to operate motor 69 for traveling the machine 45 in either direction even though limit switch 158 may be open by the mechanical action of the boom. When lever 224 is in its normal or digging position, as at 224^a, switch 334 is closed and switch 335 is opened, thus 50 making possible the operation of hoist motor 66 as well as permitting the mechanical opening of limit switch 158 to stop, as hereafter described, the rearward motion of boom and dipper.

60 To swing or rotate the platform superstructure 22 about its axis to the right or left, the operator pushes central lever 153 of the left hand master controller to his right or left respectively. When pushed to 65 the right against contact c, a secondary cir-

cuit is completed from collector shoe 144^b, through points 301, 302, 303 and 353', through safety fuse 354', through closure between lever 153 and contact c, through magnet coil 150^c to point 355, through contacts of circuit breakers 352 and 351 to point 329, through point 311 to collector shoe 144^a. The energizing of magnet coil 150^c closes contacts 150^a and 150^b thus completing a primary circuit through motor 70 which becomes operative in a direction to cause clockwise rotation of platform 22. This primary circuit is: from collector shoe 144^a, through points 311, 312 and 353, through closure of contacts 150^b, through solenoid 80 coil of circuit breaker 352 to terminal 356 of motor 70, from terminal 357 through solenoid coil of circuit breaker 351, through closure of contacts 150^a to point 321, through point 310 to collector shoe 144^c. Terminal 85 358 of motor 70 is always connected through points 330 and 301 with collector shoe 144^b. The energizing of magnet coil 150^c also closes auxiliary contacts 150^d, which closure 90 completes the same secondary circuit previously described in connection with auxiliary contacts 147^d and 146^d, thus energizing magnet coil 154^c, closing contacts 154^a and 154^b and releasing magnet brake 73 of 95 motor 70.

The closure between lever 153 and contact d completes a secondary circuit from collector shoe 144^b through points 301, 302, 303 and 353, through safety fuse 354', through closure between lever 153 and contact d, through magnet coil 149^c to point 355, through contacts of circuit breakers 352 and 351 to point 329, through point 311 to collector shoe 144^a. The energizing of magnet coil 149^c closes contacts 149^a and 149^b, thus 100 completing the following primary circuit: from collector shoe 144^a through points 311, 312 to point 353, through closure of contacts 149^b to point 350, through solenoid coil of circuit breaker 351 to terminal 357 of motor 70, from terminal 356 through solenoid coil 110 of circuit breaker 352 to point 349, through closure of contacts 149^a to point 354, through points 321 and 310 to collector shoe 144^c. The connections with terminals 356 and 357 115 are here transposed with the previous arrangement, thus motor 70 operates in the opposite direction causing left hand rotation of platform 22. The energizing of magnet coil 149^c also closes auxiliary contacts 149^d 120 which completes the same circuit through magnet coil 154^c heretofore described causing brake 73 to be released. This same circuit may be completed manually, similarly releasing brake 73, if lever 153 is pushed against contacts a or b. This makes it possible for the operator to let platform 22 "float" or rotate under its own momentum, even though motor 70 be not energized.

Electrical connections are shown for a 130

headlight at 189 and for tail-lights at 190.

While the foregoing description concerns motors, brakes, switches and controllers suitable for operation with three-phase alternating current, it is nevertheless possible to equip the shovels to operate with direct current, in which case the circuits would be somewhat different.

The means for operating the limiting switches 155 to 158 is illustrated in Figures 19 to 24 inclusive of the drawings. Referring more particularly to Figures 19 and 23, it will be seen that there is suitably mounted upon one side of the superstructure frame or platform 22 a longitudinally extending rockshaft 161. An angular stop rail 162 is arranged at the outer side of this rockshaft in parallel relation thereto and rigidly connected to said shaft at spaced points as at 163. The upper edge of said rail is provided with a vertical downwardly extending flange 164 which is adapted to be engaged by the roller 166 mounted for free rotation upon the end of a lug 165 suitably fixed to the inner side of one of the boom members 39 adjacent to its gudgeon 41. Upon the rockshaft 161 at a point intermediate of its ends an inwardly extending arm 167 is fixed, the inner end of said arm being disposed over and adapted for engagement with the lever 168 of the upper limit switch for the hoist motor 66. This switch may be of any well known construction suitable for the purpose and it will be apparent that when the hoisting motor is operated to raise the boom and the shovel, upon contact of the roller 166 with the flange 164 of the rail 162, the shaft 161 will be rocked in its bearings so that the arm 167 will actuate lever 168 to open the switch 156 and thus break the secondary circuit of the upward motion of the hoist motor although the operator's control lever is in circuit closing position. When said circuit is broken, the magnetic brake 71 instantly acts to stop the further operation of the motor.

Referring now to Figure 22, the rocking frame 61 which carries the guide pulley or sheave 60 for the cable 51 is provided with a horizontally extending arm having a channeled end which houses a coil spring 169, said spring acting upon a stop bolt 170 extending through the end of said arm to raise rocking frame 61. The lever 171 of the switch 155 overlies a projection on the end of the frame arm. Normally the rocking frame is held in the position shown in Figure 22 by cable 51 which is usually taut. If, however, during the lowering of the boom and shovel the shovel strikes any obstruction such as the mine floor before the operator stops the lowering motion of motor 66, it is apparent that cable 51 will instantly become slack and that spring 169 will tilt rocking frame 61 and sheave 60, thus permitting the lever 171 of switch 155 to move

to the latter's circuit-breaking position, thereby opening the secondary circuit of the lowering motion of motor 66, causing application of brake 71 so that further operation of the motor instantly ceases.

Referring to Figures 19 and 20, one of the boom operating chains 33 carries an inwardly projecting pin or stud 172 and as the boom reaches the end of its forward thrusting movement, this pin comes into contact with the upwardly curved end 174 of one arm of a bell crank lever 173, the other arm 175 of which carries an adjustable screw 176 for engagement with the lever 177 of the forward limiting switch 157 of the motor 69. It will thus be seen that when the bell crank lever is rocked upon its fulcrum, the switch lever 177 is actuated to open the switch 157, thus causing the application of the brake 72 and stopping the further operation of the motor 69.

The arm 175 of the bell crank lever is connected by means of the rod 178, Figures 19, 20 and 21, to an upwardly extending arm 179 on one end of a sleeve 180 which is suitably mounted for rocking movement in a bearing 181 fixed on the platform 22. The other end of this sleeve is provided with oppositely extending horizontal arms 182 and 183, respectively. The arm 183 carries an adjustable stop screw 184 which limits the rocking movement of the sleeve in one direction. An arm 185 fixed on the end of the rockshaft 161 overlies the end of the other arm 182 on said sleeve. Since the path of the shovel or dipper during forward thrusting alone is inclined upward except when it is started with its lip at the mine floor on a plane with the bottom of the tractor, in which case the path is horizontal, it will be realized that the dipper may reach the line of desired maximum elevation due to forward thrusting alone. By the mechanism above described it will be seen that should this happen the secondary circuit of the forward crowding motion of motor 69 will be opened by the opening of limit switch 157, thereby stopping said motor and causing application of brake 72. The opening of switch 157 is accomplished by the actuation of the bell crank lever arm 175 through the medium of the rod 178. The arm 185 fixed on the rockshaft also preferably carries an adjustable screw 186 to engage the arm 182 so that the time at which the switch 157 is opened in the upward and forward crowding motion of the boom (due to the operation of motor 69) may be regulated as desired.

Referring to Figure 24, the rearward travel of the boom and shovel is limited by the switch 158 which is automatically actuated by the engagement of the pin 172 with the lever 187 of said switch. As seen in Figure 24, this lever is provided with a cam portion 188 so that as the pin strikes this

cam portion of the lever and rides thereon the lever is forced downwardly to open the switch thereby breaking a secondary circuit of the motor 69 and causing the stopping of the motor and the application of its brake to stop the rearward movement of the boom.

From the above description of the construction and manner of operation of the machine, it will be seen that the several operations may be readily performed without necessitating that the single attendant shall leave his seat. The machine is also rendered practically fool-proof by the provision of the several slip frictions, fuses, circuit breakers and automatic switches. After the machine has been moved to the desired position and is engaged in the shoveling of ore and the filling of the transporting vehicle, the tractor treads are positively locked against movement in either direction so that the machine is held against casual shifting movement on the mine floor in a stationary position. The operator's knees are protected from falling or rolling pieces 25 of ore by shield 601; Figures 1, 2 and 3.

In my original application for patent above referred to, there is shown a common motor for operating the fusee and hoisting drums, said drums being provided with friction clutch devices whereby either drum may be thrown into or out of operation. Unlike the original invention however, the present improvements provide separate operating motors for the fusee drum and the hoisting 30 drum. Also in my former application the gearing for actuating the tractors is operated by the same motor which actuates the gearing for effecting the rotation of the superstructure, whereas in the improved 35 machine the boom and shovel thrusting motor actuates the tractor gearing and an additional motor is provided for the purpose of rotating the superstructure. It has been found that this arrangement provides for 40 greater flexibility in operation as well as a more positive and reliable actuation of the several operative parts. My improved machine has been employed with considerable 45 success in underground mining operations 50 for which purpose it is admirably adapted. It has heretofore been sometimes necessary, especially in the use of some machines in lead mines, to completely disassemble the parts of the machine and convey the same 55 from one location to another. This was due to the fact that the drifts or corridors between the operating locations in the mine often did not exceed six feet in height and the machine could not therefore with all its 60 parts assembled, travel through such a low corridor or passage. With a machine constructed in accordance with the present invention it has been found that the maximum height from the ground level to the upper 65 end of the boom in the position shown in

broken lines in Figure 2 of the drawings, will not be over approximately seven feet, and when the supports or standards 52 are lowered to the broken line position shown in Figure 2, this vertical overall height may be 70 decreased to less than five feet, when necessary. Thus the machine which is comparatively light in weight and will therefore be very mobile, may readily pass through connecting drifts or passages in mines having a 75 clearance of five feet. It will also be appreciated that the direct forward thrust which is imparted to the dipper or shovel in the lowered position of the boom, in contradistinction to the usual swinging movement, 80 enables the dipper to quickly fill to its capacity and to readily collect thinly scattered rock or ore. As the boom and dipper can then be retracted or drawn rearwardly until the dipper extends only a slight distance in 85 advance of the superstructure of the machine, it will be appreciated that this superstructure can be rotated and the dipper swung to its discharging position in a relatively confined space which would be impossible in machines of that type wherein the dipper remains extended while it is hoisted. As is well known, in many mining operations the roof of the working location must 90 be supported by means of numerous pillars and the present invention particularly lends itself to such use since the dipper may be readily swung to discharge into the car or vehicle at either side of the machine without encountering the supporting pillars. 95 The removal and transportation of the mined ore can thus be very greatly facilitated by means of my present invention.

In Figure 16 of the drawings I have diagrammatically illustrated the several extreme positions which may be assumed by the traveling boom and the shovel or dipper. Thus in this figure the dipper and boom are shown at 1, in the full forwardly extended position; at 2 in the forward elevated position where the dipper and boom end are at the maximum height from the ground level; at 3 in the fully retracted and lowered position; and at 4, in the fully retracted and elevated position. In addition, as above explained, the boom and shovel may be lowered from the position shown at 4 in Figure 16 by swinging the supports 54 forwardly and downwardly as above referred to and as indicated in broken lines in Figure 2 of the drawings, when it may become necessary to decrease the overall vertical height during the travel of the machine from one location to another.

In the invention and design of this machine it has been my endeavor throughout to imitate as closely as possible the various motions and combinations of motions which are used by a manual laborer shoveling ore with a spade. For example, the forward 125

thrusting or crowding of the dipper is analogous to the forward thrusting of a hand spade; a combination of forward thrusting and upward hoisting of the dipper is analogous to an inclined upward digging motion used by the laborer; the rotating of the superstructure is similar to the rotation of the body of the laborer as he swings his spade to a point over the ore car. The ability to retract the boom and dipper in order that in rotating it may clear any obstruction such as a mine pillar, and the ability to further retract it or again reach out in order that the dipper may dump into the transporting vehicle, are both comparable to the functioning of the laborer. The analogy is further exemplified by the capability of the machine to be lowered in maximum height in order to make possible its passage through a low drift or tunnel, which may be compared to the laborer walking through such a drift in a crouching position.

I have herein referred to the use of my improved machine particularly in connection with the mining of lead ore and for this purpose have illustrated an embodiment of the invention which has been found to be entirely practical in actual use. It will nevertheless be entirely obvious that such a machine is also adaptable to various other uses of an analogous nature. Possibly also in such other adaptations of my invention it may become necessary to make certain structural, mechanical and electrical changes in the various parts of the machine. Since, however, it is manifest that a machine of this character might be exemplified in numerous other alternative constructions than that herein specifically disclosed, it is to be understood that the privilege is reserved of resorting to all such legitimate changes in form, construction and the relative arrangement of the several elements as may be fairly considered within the spirit and scope of the invention as claimed.

I claim:

1. In a shoveling machine, a frame, a boom, and means supporting said boom at one of its ends upon the frame for rectilinear traveling movement and vertical swinging movement, a dipper carried by the other end of said boom, mechanism for effecting a rectilinear movement of the boom relative to the frame, mechanism for swinging said boom vertically, a separate operating motor for each of said mechanisms, and manual control means for the respective motor circuits whereby combined rectilinear and vertical swinging movements, or either of such movements independently of the other, may be imparted to the boom at the option of the operator.

2. In a shoveling machine, a frame, a vertically swinging boom mounted to travel lon-

gitudinally upon said frame, a dipper carried by the forward end of said boom, a shaft and operating connections between said shaft and the boom to project and retract said boom, a boom hoisting drum supported upon said shaft, and independently controllable motors for actuating said shaft and the hoisting drum.

3. In a shoveling machine, a vertically swinging and longitudinally traveling boom, a dipper carried by said boom, a cable connected to said boom, a fusee drum to which one end of the cable is attached, means for moving the boom to effect a forward longitudinal thrust or a rearward retracting motion of the dipper and for simultaneously operating the fusee drum to respectively unwind the cable or wind the cable thereon, and means for independently operating said hoisting drum to wind the cable thereon or unwind said cable therefrom and thereby swing the boom to respectively elevate or lower the dipper.

4. In a shoveling machine, a vertically swinging and longitudinally traveling boom, a dipper carried by said boom, a cable connected to said boom, a shaft and operating connections between said shaft and the boom to project and retract the boom, a fusee drum to which one end of said cable is attached, a hoisting drum loosely mounted on the shaft to which the other end of said cable is attached, and independently controllable motors for actuating said shaft and the hoisting drum.

5. In a shoveling machine, a rotatably mounted superstructure, a vertically swinging boom mounted to travel longitudinally upon the super-structure, a dipper carried by said boom, a cable connected to said boom, a fusee drum to which one end of the cable is attached, a hoisting drum to which the other end of the cable is attached, means for moving the boom to effect a thrusting or retracting motion of the boom and dipper and for simultaneously actuating the fusee drum, means for independently operating said hoisting drum to wind up or unwind the cable at any point in such thrusting or retracting movement of the boom to thereby swing the boom and respectively elevate or lower the dipper, and means independent of the boom operating means for rotating said super-structure to swing the dipper horizontally to discharging position.

6. In a shoveling machine, a frame supporting tractors therefor, a superstructure rotatably mounted upon said frame, longitudinally traveling carriages on opposite sides of the superstructure, a boom pivotally mounted upon the carriages for vertical swinging movement, a dipper carried by said boom, means for imparting a longitudinal travel to the carriages to effect a forward thrusting or retracting motion of the

dipper, independent means for swinging the boom vertically to elevate or lower the dipper, and additional independent means to rotate the superstructure thus swinging the dipper horizontally to a discharging position.

7. In a shoveling machine, a frame supporting tractors therefor, a superstructure rotatably mounted upon said frame, longitudinally traveling carriages on opposite sides of the superstructure, a boom pivotally mounted upon the carriages for vertical swinging movement, a dipper carried by said boom, means for imparting a longitudinal travel to the carriages to effect a forward thrusting or retracting motion of the dipper, independent means for swinging the boom vertically to elevate or lower the dipper, additional means to rotate the superstructure thus swinging the dipper horizontally to a discharging position, propelling mechanism for the tractors, and means for operatively connecting either the propelling mechanism or the boom thrusting or retracting means 25 to a common source of power.

8. In a shoveling machine, a frame structure, a boom mounted thereon for vertical swinging and longitudinal traveling movement, a dipper carried by said boom, a cable 30 connected with said boom, a hoisting drum for the cable, a support pivotally mounted upon the frame and having guides for the cable mounted thereon limiting the movement of the boom to an elevated position, the 35 said support adapted to be swung downwardly to a position adjacent the frame structure when the machine is not in use and means for sustaining the support in an upright operative position.

9. In a shoveling machine, a vertically swinging and longitudinally traveling boom, a dipper carried by said boom, means for projecting and retracting the boom and dipper, a fusee drum operable with the latter 45 means, an independently rotatable hoisting drum, a cable attached to said drums and connected to the boom, and independently controllable reversible motors for operating the fusee drum with the boom projecting and 50 retracting means and the hoisting drum respectively.

10. In a shoveling machine, a vertically swinging and longitudinally traveling boom, a dipper carried by said boom, means for projecting and retracting the boom and dipper, a fusee drum, a hoisting drum, a cable 55 attached to said drum and connected to the boom, and independently controllable reversible motors for operating said fusee 60 drum with the boom projecting and retracting means and the hoisting drum respectively to take up or pay out the cable in the longitudinal travel of the boom or in the vertical swinging movement thereof.

11. In a shoveling machine, a frame sup-

porting tractors therefor, a boom mounted to travel longitudinally thereon, a dipper carried by said boom, means for projecting or retracting said boom and dipper, operating gearing for the tractors, a reversible 70 motor, and manually operable means for connecting said motor either to the boom operating means or to the tractor operating means.

12. In a shoveling machine, a frame supporting tractors therefor, a boom mounted to travel longitudinally thereon, a dipper carried by said boom, means for projecting or retracting said boom and dipper, operating gearing for the tractors, a reversible 75 motor, manually operable means for connecting said motor either to the boom operating means or to the tractor operating means, and means for locking the tractors against movement during the shoveling operation.

13. In a shoveling machine, a frame supporting tractors therefor, a superstructure rotatably mounted upon said frame, a vertically swinging and longitudinally traveling boom mounted on the superstructure, a dipper carried by said boom, means for projecting and retracting the boom and dipper, means for swinging the boom vertically, means for rotating the superstructure to 90 swing the boom and dipper horizontally, and independently operable reversible motors for actuating the boom projecting and retracting means, the boom swinging means and the superstructure rotating means, respectively. 95

14. In a shoveling machine, a frame supporting tractors therefor, a superstructure rotatably mounted upon said frame, a vertically swinging and longitudinally traveling boom mounted on the superstructure, a dipper carried by said boom, means for projecting and retracting the boom and dipper, means for swinging the boom vertically, means for rotating the superstructure to 105 swing the boom and dipper horizontally, independently operable reversible motors for actuating the boom projecting and retracting means, the boom swinging means and the superstructure rotating means, respectively, operating mechanism for the tractors, and manually operable means for disconnecting one of said motors from the boom operating means and connecting said motor to the tractor actuating means at the option 110 of the operator. 115

15. In a shoveling machine, a frame supporting tractors therefor, a superstructure rotatably mounted upon said frame, a vertically swinging and longitudinally traveling boom mounted on the superstructure, a dipper carried by said boom, means for projecting and retracting the boom and dipper, means for swinging the boom vertically, means for rotating the superstructure to 123

swing the boom and dipper horizontally, independently operable reversible motors for actuating the boom projecting and retracting means, the boom swinging means and the superstructure rotating means, respectively, means for operating the tractors, and manually operable means for disconnecting one of the reversible motors from the boom projecting and retracting means and connecting said motor to the tractor operating means at the option of the operator.

16. In a shoveling machine, a frame supporting tractors therefor, a superstructure rotatably mounted upon said frame, a vertically swinging and longitudinally traveling boom mounted on the superstructure, a dipper carried by said boom, means for projecting and retracting the boom and dipper, means for swinging the boom vertically, means for rotating the superstructure to swing the boom and dipper horizontally, independently operable reversible motors for actuating the boom projecting and retracting means, the boom swinging means and the superstructure rotating means, respectively, means for operating the tractors actuated by one of said motors, and means for locking the tractors against movement during the shoveling operation.

17. In a shoveling machine, a frame, a dipper mounted and arranged for longitudinal traveling movement and vertical swinging movement with respect to said frame, mechanism for longitudinally projecting and retracting the dipper relative to the frame, mechanism for vertically swinging the dipper, separate motors mounted upon the frame for independently actuating said mechanisms, propelling mechanisms for the machine, and manually operable means for disconnecting one of said motors from the dipper actuating mechanism and simultaneously connecting the said motor to the machine propelling mechanism.

18. In a shoveling machine, a frame supporting tractors therefor, a rotatable superstructure mounted upon said frame, shoveling mechanism carried by the superstructure, operating mechanism for the tractors partially mounted in the superstructure and partially mounted in the main frame, and means for locking the tractor operating mechanism to retain the main frame in a stationary position against casual shifting movement.

19. In a shoveling machine, a rotatable superstructure, a longitudinally traveling and vertically swinging boom and dipper mounted thereon, propelling mechanism for the machine, mechanism for projecting and retracting the boom and dipper, a common reversible motor for operating said propelling mechanism or the boom projecting and retracting mechanism at the will of the operator, means for vertically swinging the

boom and dipper, a second reversible motor for operating the latter means, mechanism for rotating the superstructure to swing the boom and dipper horizontally, a third reversible motor for operating said superstructure rotating mechanism, all of said motors being mounted upon the superstructure, an operator's seat on the superstructure, and controls for said reversible motors arranged at either side of the operator's seat.

20. In a shoveling machine, a frame, a boom mounted at one of its ends upon said frame for rectilinear traveling movement and vertical and horizontal swinging movement with respect to the frame, a relatively stationary dipper mounted upon the other end of said boom, mechanism for effecting rectilinear movement of the boom, mechanism for swinging the boom vertically, mechanism for swinging the boom horizontally, a separate operating motor for each of said mechanisms, and manual control means for the respective motor circuits whereby a combined rectilinear and vertical and horizontal swinging movements or any one of such movements independently of the others may be imparted to the boom at the option of the operator.

21. In a shoveling machine, a material collecting dipper mounted and arranged to travel in a horizontal plane and for vertical swinging movement, means for projecting and retracting the dipper horizontally, additional means for vertically swinging the dipper, a separate reversible electric motor for each of said dipper operating means, manually operable control means for energizing the motors independently of each other, and automatically actuated switches arranged in the motor circuits for de-energizing said motors independently of the manually operable control means and thereby limiting the horizontal traveling movement of the dipper in each direction and also the vertical swinging movements of said dipper.

22. In a shoveling machine, a frame, a dipper mounted for longitudinal traveling and vertical swinging movement relative to the frame, means for moving the dipper longitudinally including a motor, means for swinging the dipper vertically including a motor, separate manually operable controls for said motors, and means automatically actuated when the dipper is swung vertically at any point in its longitudinal traveling movement for rendering said first named motor inoperative.

23. In a shoveling machine, a frame, a dipper mounted for longitudinal traveling and vertical swinging movement relative to the frame, means for moving the dipper longitudinally including a motor, means for swinging the dipper vertically including a motor, separate manually operable controls

for said motors, and means automatically operated independently of the manual motor controls when the dipper is swung upwardly to a predetermined elevation above the frame to render said first named motor inoperative.

24. In a shoveling machine, a frame, a dipper mounted for longitudinal traveling and vertical swinging movement relative to the frame, means for moving the dipper longitudinally including a motor, means for swinging the dipper vertically including a motor, separate manually operable controls for said motors, and switches interposed in the motor circuits and automatically operable independently of the manual motor controls when the dipper is vertically swung upwardly to a predetermined elevation above the frame at any point in its longitudinal traveling movement to thereby de-energize both of the said motors.

25. In a shoveling machine, a frame, a dipper mounted for rectilinear traveling movement and vertical and horizontal swinging movement with respect to the frame, mechanism for effecting a rectilinear movement of the dipper, mechanism for swinging the dipper vertically, mechanism for swinging the dipper horizontally, a separate operating motor for each of said mechanisms, and manual control means for the respective motor circuits whereby a combined rectilinear and vertical and horizontal swinging movements or any one of such movements independently of the others may be imparted to the dipper at the option of the operator.

In testimony that I claim the foregoing as my invention, I have signed my name hereunder.

ARTHUR K. MITCHELL.
